(57) **CLAIM**

The ornamental design for a buckle for bag, as shown and described.

DESCRIPTION

FIG. 1 is a front, top, and right side perspective view of a buckle for bag, showing our new design;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof;
FIG. 8 is a cross-sectional view taken along line 8-8 shown in FIG. 2;
FIG. 9 is a front, top, and right side perspective view of the buckle for bag, of FIG. 1;
FIG. 10 is a front, top, and right side perspective view of the buckle for bag of FIG. 1, shown in an open state; and,
FIG. 11 is a front view of the buckle for bag of FIG. 1, shown in a state of use.
The broken lines in FIG. 11 represent environmental subject matter only and form no part of the claimed design. The dot-dash lines in FIG. 2 represent cross sectional view indicia only and form no part of the claimed design.
